ELECTROLYTIC CELL STRUCTURE

David W. Morgan, Los Altos, Calif., assignor to Kaiser Aluminum & Chemical Corporation, Oakland, Calif., a corporation of Delaware
Filed June 24, 1958, Ser. No. 744,162
20 Claims. (Cl. 204—244)

Our invention relates in general to electrolytic cells for the production of metal. More particularly, the invention relates to new and improved arrangements for refractory hard metal cathodic current conducting elements for aluminum reduction cells. As used hereinafter, the expression "RHM" means "refractory hard metal."

The use of RHM negative current conducting elements, i.e. cathodic elements, in aluminum reduction cells has been previously disclosed in French Patent 1,064,743. In the French patent there are revealed three arrangements of RHМ cathodic current conducting elements for use in aluminum reduction cells. These three arrangements are (1) horizontal side entering wherein the elements extend horizontally through the vertical side walls of the reduction cell and project at their interior extremities into the molten aluminum layer, (2) top entering elements wherein the elements pass through the solidified crust and molten electrolyte along the side walls of the cell and terminate at their extremities a short distance above the base of the cell, and (3) the current conducting elements are disposed vertically and introduced into the molten electrolyte layer through the base of the electrolytic cell. In all of these arrangements the cathodic current conducting elements are distributed along the length of the cell cavity or chamber.

All of the above-described arrangements for RHМ cathodic current-conducting elements have significant disadvantages. One of the problems encountered in the operation of electrolytic cells employing such elements is mechanical breakage of the elements. The elements may be broken by abuse during raking, by stress imposed through adhering crust during anode adjustment, or by deformation of the cell structure supporting the elements. Another problem with such elements is the necessity of maintaining the elements in the cathode metal layer in direct contact with the metal. If the heat generation in a particular section of the cell cavity is reduced below normal, a ledge of frozen electrolyte may grow on the walls and bottom of the cavity around that section, and this ledge may envelope and cover any elements near it, thereby breaking direct contact between the elements and the metal.

A further problem lies in preventing muck (a loose mixture of undissolved alumina and frozen electrolyte or bath which sinks through the cathode metal layer) from building up under the cathode metal layer and disrupting the cathode surface or interfering with the necessary flow of current in the cathode metal layer. This problem is more pronounced in cells employing RHМ current conducting elements than it is in conventional cells employing steel collector bars embedded in a carbon bottom wall or floor because the net heat flow across the bottom surface of the cavity is away from the cavity rather than into the cavity as in the case of conventional cells, thereby making the muck lying on the bottom of the cavity cooler than the adjacent cathode metal. This makes the muck harder and more difficult to remove.

A further problem in the operation of electrolytic cells employing RHМ cathodic current conducting elements lies in the effect of turbulence from electromagnetic forces induced in the metal and the electrolyte by the magnetic fields resulting from the heavy electrical currents required for the reduction process. These forces may cause excessive movement and surging of the molten

2

electrolyte and/or metal. The forces are more of a problem in cells employing RHМ elements than in conventional cells because of the greater distance the current must travel in the cathode metal layer.

The arrangement of cathodic elements discussed above have failed to offer solutions to these problems. For example, a cell with horizontal side entering cathodic elements, (1) above, has exhibited difficulties with muck under the cathode metal layer and with excessive ledging of frozen bath enveloping the cathodic elements. In this arrangement, electromagnetic disturbance has been excessive, and the total distance traveled by the current is more than is desirable. In cells with top entering cathodic elements along the side walls of the cell, (2) above, the elements interfere with normal cell operations, particularly with breaking in of the crust at the sides of the cavity. This arrangement has problems with electromagnetic disturbances and muck, also. In cells with bottom entering cathodic elements, (3) above, the elements are very susceptible to damage during raking. Also, the total distance the current must travel in this arrangement is excessive.

As used here in the specification and the claims, the expression "RHМ" or "refractory hard metal" refers to a material which possesses a low electrical resistivity, a low solubility in molten aluminum and molten electrolyte under cell operating conditions, is wettable by molten aluminum under cell operating conditions, and has good stability under conditions existing at the cathode of a reduction cell. The preferred refractory hard metal material for at least that portion of the surface of such element in contact with the molten aluminum consists essentially of at least one of the materials selected from the group consisting of the carbides and borides of titanium, zirconium, tantalum, and niobium, and mixtures thereof, such materials being found to exhibit all or substantially all of the above properties.

The expression "consists essentially," as used herein-after in the specification and the claims, means that the RHМ material does not contain other substances in amounts sufficient to materially affect the desirable characteristics of the material, although other substances may be present in minor amounts which do not materially affect such desirable characteristics, for example, small proportions of oxygen, nitrogen and iron in titanium boride.

Therefore, it is the principal object of the invention to present new and improved arrangements for RHМ cathodic current-conducting elements for aluminum reduction cells which overcome or substantially reduce the disadvantages of prior art arrangements.

It is a further object of the invention to present improved arrangements for RHМ current-conducting cathodic elements wherein the elements will not be subject to mechanical breakage during operation of the electrolytic cell.

It is also an object of the invention to provide improved arrangements of RHМ cathodic elements for aluminum reduction cells, said arrangements permitting cell operation with maximum convenience and minimum maintenance, labor, and skill on the part of the operators.

It is a still further object of the invention to provide an improved design for an electrolytic cell employing RHМ cathodic current-conducting elements wherein the total distance through which the current must travel in and between cells is substantially lessened.

It is also an object of the invention to provide an arrangement for a plurality of electrolytic cells employing RHМ cathodic current-conducting elements wherein the total distance through which the current must travel in and between cells is substantially lessened.

It is a still further object of the invention to provide

improved arrangements of RHM cathodic current-conducting elements for aluminum reduction cells wherein the effect of electromagnetic forces in the electrolyte and metal in the cell is minimized thereby preventing excessive movement and surging of the electrolyte and/or metal.

These and other objects and advantages will be apparent from the ensuing description of the invention when taken in view of the accompanying drawings.

The invention generally comprises arrangements for RHM cathodic current-conducting elements for elongated (that is, the side walls are relatively longer than the end walls) aluminum reduction cells or pots which are electrically connected in series in a potline. The elements are disposed in the cells in one or more rows transversely across the cell, that is, across the width or shortest horizontal dimension of the cell. One extremity of each cathodic current-conducting element is adapted to extend into the molten aluminum pool of the cell while the other extremity is exposed to the atmosphere and is connected to a metallic conductor. The arrangements are suitable for electrolytic cells employing either prebake anodes or self-baking (Soderberg) anodes. By disposing the elements in at least one row transverse across the cell, the cell can be operated with maximum convenience, and minimum maintenance, labor, and skill on the part of the operator. Furthermore, placement of the elements according to the invention lessens the total distance through which the current must travel in and between cells in order to perform its function of reducing an aluminum-containing compound, e.g. alumina, to make aluminum metal. Also, the arrangements for the elements as taught herein substantially reduces electromagnetic disturbance of the molten metal and electrolyte which has been excessive in previous electrolytic cells employing RHM cathodic current-conducting elements.

In the accompanying drawings are illustrated several embodiments of the instant invention as applied to aluminum reduction cells.

In the drawings:

FIGURE 10 is a plan view of a plurality of aluminum reduction cells showing a further embodiment of the invention as applied to cells arranged in end to end relationship;

FIGURE 11 is a view taken along the line 11-11 of FIGURE 10; and

FIGURE 12 is a view taken along the line 12-12 of FIGURE 10.

Referring now in particular to FIGURES 1, 2 and 3, there is shown an arrangement for RHM cathodic elements for electrolytic reduction cells electrically connected in series and arranged in side by side relationship.

The elongated cells 10 are electrically connected in series and are placed in side by side relationship, that is, the side wall of one cell is parallel and adjacent to a side wall of a neighboring cell. Each cell 10 has a metal shell 11, e.g. of steel, within which is disposed in the usual manner an insulating lining 12 which can be of any desired insulating material, such as alumina, bauxite, clay or aluminum silicate bricks. Within insulating lining 12 is disposed refractory lining 13, which can be of any desired material, for instance, carbon, alumina, fused alumina, silicon carbide, silicon nitride bonded silicon carbide or other desired materials. Most commonly the lining is made up of a plurality of carbon blocks or is a rammed carbon mixture or a combination of a rammed carbon mixture for the bottom or floor of the lining with side and end walls constructed of blocks of carbon. Alternatively, the side and end walls can be constructed of silicon carbide bricks or other suitable material. The lining 13 defines a cavity or chamber within which is disposed a pool or layer of molten aluminum 14. Also disposed within the chamber and in contact with the aluminum layer 14 is a body or layer 15 of molten electrolyte, e.g., cryolite. The electrolyte 15 is covered by a solid crust layer 16, which consists essentially of frozen electrolyte constituents and additional alumina. As alumina is consumed in electrolyte 15, the frozen crust is broken and more alumina fed into the electrolyte.

Disposed above cells 10 are anode bus bars 17 which are supported by any suitable means (not shown). Pre-bake anodes 18, for introducing electrical current into the cell, are shown supported from bus bars 17 by means of rods 19 which are connected to bus bars 17 by any suitable means, such as by clamping. Anodes 18 are preferably rectangular carbon blocks and are disposed within the chamber defined by the walls and floor of the cell in rows parallel to the longitudinal axis of the cell. Anodes 18 depend downwardly into the body of molten electrolyte 15. Bus bars 17 are H-shaped, as shown in FIGURE 1, and the current from the adjacent cathode bus 20 flows to the center of anode bus 17 and then flows equally towards the ends of bus 17.

Cathode bus bars 20 are supported by suitable means (not shown) above cells 10. RHM cathodic elements 21 are connected to cathode bus bars 20 by suitable means and are disposed transversely in at least one row across the longitudinal midsection of cells 10. In FIGURES 1, 2 and 3, two rows of elements 21 are shown disposed transversely across the cell. Elements 21 depend vertically downward and extend down into the molten aluminum pool 14. The elements may extend from cathode bus bar 20; however, this requires a relatively long length of RHM material which would substantially increase the cost of the element. A more economical design is as shown in FIGURES 1, 2 and 3 wherein relatively short elements 21 extend from just above the crust layer 16 down into the molten aluminum layer 14. Suitable metallic conductor members, e.g. of aluminum, 23 are joined by suitable means to elements 21 which are in turn joined by suitable means to cathode bus members 20.

The RHM elements may be joined to aluminum conductor members by a procedure which is disclosed in the co-pending application of Jack L. Henry, Serial No. 729,621, filed April 21, 1958. This procedure generally comprises a cleaning of the RHM member at the portion of the surface where the joint is to be made, preheating the RHM member to a temperature above the melting point of aluminum, contacting the RHM member while at said preheating temperature with a molten flux consisting essentially of the fluorides of sodium, aluminum and lithium and sodium chloride, and then contacting the RHM member with molten aluminum after which the RHM member and aluminum are allowed to cool. The joint which is formed between the RHM member and the aluminum has superior mechanical strength and electrical conductivity characteristics.

Preferably, suitable members are disposed within the cell to protect elements 21 from damage during crust breaking operations. An example of suitable means are rigid frame members 24 which are transversely disposed across the cells 10 adjacent elements 21 and fastened to the side walls of cells 10 in any suitable manner. Frame members 24 depend downwardly into the crust layer 16 as shown in FIGURES 1, 2 and 3, so that breaking of the crust layer 16 during feeding operations will not affect or disrupt that portion of the crust 16 adjacent elements 21.

As shown in FIGURES 1, 2 and 3, the cells 10 are electrically connected in series, that is, the anode bus bars of one cell are connected to the cathode bus of an adjacent cell by means of flexible metal connections 22 which are suitably joined to anode bus bars 17 and cathode bus bars 20 by any suitable means, such as welding.

By placing the elements transversely across the midsections of cells 10, the problem of growth of muck deposits under the cathode metal is substantially reduced since the entire ends of the cells are free of RHM elements and open to efficient raking. In addition, muck may be raked to both sides and ends of the cell, where it can come in contact with the electrolyte and be dissolved. Further help in controlling muck is afforded by the electromagnetic characteristics of the cells shown in FIGURES 1, 2 and 3, wherein the cathode metal will flow more rapidly in the midsection of the cell and more slowly towards the ends, thereby promoting removal of muck from the midsection of the cell and depositing it towards the ends.

The electromagnetic forces in the cell depicted in FIGURES 1, 2 and 3 are substantially reduced and are useful in controlling muck. The reduction of the electromagnetic forces in the cells may be ascribed to the fact that in the critical region in the midsection of the cell where the current in the cathode metal is greatest, the magnetic fields set up by the currents in the two end halves of the anode bus bars are compensating, since the current travels out from the midsection of the anode bus in equal amounts but opposing directions in each side. In a similar manner the fields set up by the currents coming into the elements in the midsection of the cell through the cathode metal layer tend to compensate. Further, the problem of electromagnetic surging of the cathode metal is further reduced by the effect of the elements in damping end-to-end movement of metal. The elements form a barrier across the cell, thereby appreciably restricting the flow of metal and electrolyte past the midsection of the cell.

Placing the elements transversely across the midsections of the cells does not interfere with raking muck in the cells, anode setting, or breaking-in the side crust. In the embodiment shown in FIGURES 1, 2 and 3, the alumina may be fed to the cells in the conventional manner by breaking crust in the center of the cell between the longitudinal rows of anodes with a poker and then puddling in the alumina. Further, the poker employed to feed the cell and to rake muck in the bottom may be made shorter than in cells of other designs, since the poker does not need to reach past the midsection of the cell, but only up to the elements. With a shorter poker it is easier to rake muck from under the end anodes, where with a normal poker, raking is a problem. Also, the need for anode adjustment is greatly reduced by the reduced problems of muck and the increased stability of the cathode metal which results from the more favorable electromagnetic and current-flow characteristics.

The total distance through which the current must flow in the cells depicted in FIGURES 1 through 3 is less than in those arrangements where the current must pass either beyond the ends of the cell, as in all end-fed-bus arrangements, or beyond the sides of the cell as in all arrangements employing cathode ring bus.

FIGURES 4, 5 and 6 depict a further embodiment of the invention for electrolytic cells connected electrically in series and placed in side-by-side relationship. In these FIGURES, each cell 30 has a metal shell 31, e.g. of steel, within which is disposed in the usual manner an insulating lining 32 which can be of any desired insulating material, such as alumina, bauxite, clay or aluminum silicate bricks. Within insulating lining 32 is disposed refractory lining 33, which can be of any desired material, for instance, carbon, alumina, fused alumina, silicon carbide, silicon nitride bonded silicon carbide or other desired materials. The lining 33 defines a cavity or chamber within which is disposed a pool or layer of molten aluminum 34. Also disposed within the chamber and in contact with the aluminum pool 34 is a body 35 of molten electrolyte, e.g. cryolite. The electrolyte 35 is covered by solid crust layer 36, which consists essentially of frozen electrolyte constituents and additional alumina.

Disposed above cells 30 are anode bus bars 37 which are supported by any suitable means (not shown). Pre-bake anodes 38 for introducing electrical current into the cell are shown supported from bus bars 37 by means of rods 39 which are connected to bus bars 37 by any suitable means, such as by clamping. Anodes 38 are preferably rectangular carbon blocks and disposed within the chamber defined by the walls and floor of the cell in rows parallel to the longitudinal axis of the cell. Anodes 38 depend downwardly into the body of molten electrolyte 35. Bus bars 37 are H-shaped, and, as shown in FIGURE 4, two such bus bars are disposed above each cell. The current from an adjacent cathode bus 40 flows to an anode bus 37 at the midway point and then flows equally towards the ends of bus 37.

Although the embodiment in FIGURES 4, 5 and 6 depicts two H-shaped anode bus bars disposed above each cell, the embodiment is not limited thereto. A satisfactory arrangement of one bus bar disposed above the cell is one comprised of two parallel members disposed parallel to the long dimension of the cell and joined by two cross members, one cross member being located above each midway point between the midsection and the end walls of the cell. This structure can be simply described as joining the ends which are adjacent the midsection of the cell of the two H-shaped bus bars depicted in FIGURES 4, 5 and 6.

Cathode bus bars 40 are supported by suitable means (not shown) above cells 30. RHM cathodic elements 41 are connected to bus bars 40 by suitable means and are disposed transversely across the cells 30 in two rows, one row being at each midpoint between the midsection and the ends of the cells. Elements 41 depend vertically downward and extend into the molten aluminum pool 34. In FIGURES 5 and 6 the elements 41 are shown as relatively short elements extending from just above the crust layer 36 down into the molten aluminum pool 34. Suitable metallic conductor members, e.g. of aluminum, 43 are joined by suitable means to elements 41 and are in turn joined by suitable means to cathode bus members 40. Rigid frame members 44 are transversely disposed across the cells 30 adjacent to and on either side of the transverse rows of elements 41, said members 44 depending downwardly into crust 36.

In the cells depicted in FIGURES 4, 5 and 6, the electromagnetic forces are reduced to a level within the order of that found in present day cells and are even useful in controlling the problem of muck. The magnetic fields set up by the currents in the two end halves of each H-shaped anode bus are compensating, and in a similar manner the fields set up by the currents coming into elements 41 which are disposed in two transverse rows, one row being at substantially each of the halfway or midway points between the midsection and ends of the cells, tend to compensate. Also, the problem of electromagnetic surging of the cathode metal is reduced by the effect of the elements

damping end to end movement of metal. The elements 41 form barriers across the cell which will appreciably restrict the flow of metal and electrolyte.

FIGURES 7, 8 and 9 show an arrangement for RHM cathodic elements for electrolytic reduction cells electrically connected in series and arranged in end to end relationship. The elongated cells 50 are electrically connected in series and are placed in end to end relationship, that is, an end wall of one cell is parallel and adjacent to an end wall of a neighboring cell. Each cell 50 has a metal shell 51, e.g. of steel, within which is disposed in the usual manner an insulating lining 52 which can be of any desired insulating material, such as enumerated previously in description of FIGURES 1, 2 and 3. Within insulating lining 52 is disposed refractory lining 53, which can be of any desired material as described previously. The lining 53 defines a cavity or chamber within which is disposed a pool or layer of molten aluminum 54. Also disposed within the chamber and in contact with the aluminum 54 is a body 55 of molten electrolyte, e.g. cryolite. The electrolyte body 55 is covered by a solid crust layer 56.

Disposed above cells 50 are anode bus bars 57 which are supported by any suitable means (not shown). Self-baking anodes 58 for introducing electrical current into the cell are electrically connected to bus bars 57 and are supported by suitable means (not shown). It is usual practice with self-baking anode cells to employ a single anode per cell; however, more anodes, e.g. two anodes, could be used. The anodes 58 depend downwardly into electrolyte 55.

Cathode bus bars 60 are supported by suitable means (not shown) above cells 50. Relatively short RHM cathodic elements 61 are joined by suitable means to metallic conductor elements 63 which in turn are joined by suitable means to cathode bus bars 60. The elements are disposed vertically and transversely in at least one row across the downstream end of each cell, that is, the end of the cell where the current leaves the cell and enters the anode bus of an adjacent cell. Elements 61 depend downwardly from above the crust 56 and extend through electrolyte 55 and into the molten aluminum pool 54.

Rigid frame members 64 are disposed transversely across the cells 50 adjacent to elements 61, said members 64 depending downwardly into crust 56.

As shown in FIGURES 7, 8 and 9, the cells 50 are electrically connected in series, that is, the cathode bus bars of one cell are connected to the anode bus of an adjacent cell by means of flexible metal connections 62 which are joined to cathode bus bars 60 and anode bus bars 57 by any suitable means, such as welding.

FIGURES 10, 11 and 12 show an alternative arrangement for RHM cathodic elements for electrolytic cells arranged in end to end relationship. The elongated cells 70 are electrically connected in series and are placed in end to end relationship. Each cell 70 has a metal shell 71, e.g. of steel, within which is disposed an insulating lining 72 which can be of any desired insulating material as discussed previously. Within insulating lining 72 is disposed refractory lining 73 which can be of any desired material as previously discussed. The lining 73 defines a cavity or chamber within which is disposed a pool or layer of molten aluminum 74. Also disposed within the chamber and in contact with the aluminum pool 74 is a body 75 of molten electrolyte, e.g. cryolite. The electrolyte 75 is covered by a solid crust layer 76 which consists essentially of frozen electrolyte constituents and additional alumina. Disposed above cells 70 are anode bus bars 77 which are supported by any suitable means (not shown). Self-baking anodes 78 for introducing electrical current into the cell are electrically connected to bus bars 77 and are supported by suitable means (not shown). Anodes 78 depend downwardly into electrolyte 75.

Cathode bus bars 80 are supported by suitable means (not shown) and are disposed across the downstream end

of said cells 70. Cathodic elements 81 are connected to cathode bus bars 80 by suitable means and are disposed transversely in at least one row across the downstream end of said cells 70. Elements 81 extend horizontally through suitable openings provided in the metal shell 71, insulation layer 72 and refractory lining 73 with the inner extremity thereof projecting into the layer or pool of molten aluminum 74. The cells 70 are electrically connected in series, that is, the anode bus bars are connected to the cathode bus of an adjacent cell by means of flexible metal connections 82 which are suitably joined to anode bus bars 77 and cathode bus bars 80 by any suitable means such as welding.

Cells 70 are electrically connected in series, that is, the cathode bus bars of one cell are connected to the anode bus of an adjacent cell by means of flexible metal connections 82 which are joined to cathode bus bars 80 and anode bus bars 77 by any suitable means, such as welding.

In the embodiments shown in FIGURES 7 through 9 and FIGURES 10 through 12, the placing of the cathodic elements transversely across the downstream ends of the cells substantially reduces the problem of mechanical breakage of elements during raking and feeding, since the elements are grouped at the end of the cavity away from the regions of feeding and raking. Also, in the embodiment shown in FIGURES 7 through 9, mechanical breakage of the vertical refractory hard metal elements by crust movement is precluded by the rigid frame members.

The problem of maintaining direct contact between the RHM elements and the cathode metal is alleviated by both embodiments since the elements are grouped together in the downstream end of each cell where a maldistribution of current due to a dead section of anode will have little effect and cannot cause ledging which would cover the elements. The problem of growth of muck deposits under the cathode metal is also alleviated because the chamber or cavity is substantially free of cathodic elements and open to efficient raking. Muck accumulation at the downstream end where the cathodic elements might impede raking will be repressed by movement of the metal caused by electromagnetic forces.

The electromagnetic forces in the arrangements shown in FIGURES 7 through 9 and FIGURES 10 through 12 will be kept to an acceptable level by the disposition of the RHM elements across the width of the chamber or cavity and by the high and widely-spaced arms of the anode bus, which are usual in self-baking (Soderberg) cells. The region of greatest electromagnetic forces in the cell will be at the downstream end, where electromagnetic force is desirable to gain sufficient metal movement to inhibit muck accumulation near the elements. Moreover, the arrangements shown in FIGURES 7 through 9 and FIGURES 10 through 12 improve cell operation since in each embodiment the elements are grouped away from the region of the chamber requiring raking, and from the region in which the cell is fed alumina. The region near the refractory hard metal elements themselves will require little attention since this area or this region is kept clean by the movement of the cathode metal. Also, the total distance through which the current must flow is minimized.

Although, in the embodiments depicted in FIGURES 1 through 3 and FIGURES 4 through 6, prebake anodes are specifically shown and discussed, it is to be understood that these embodiments may also be employed with reduction cells employing self-baking (Soderberg) anodes. Likewise, in the embodiments depicted in FIGURES 7 through 9 and FIGURES 10 through 12, wherein self-baking (Soderberg) anodes are specifically shown and discussed, it is to be understood that these embodiments may also be employed with prebake anodes. Further, it is to be distinctly understood that the invention is not limited to the illustrative embodiments presented and that various changes may be made without departing from the spirit and scope thereof, the invention being limited only as

defined in the following claims wherein what is claimed is:

1. A plurality of elongated electrolytic cells for the production of aluminum, said cells connected electrically in series and having an arrangement of cathodic current-conducting elements, each cell comprising refractory side and end walls, said side walls being relatively longer than said end walls, a floor of a refractory material, said walls and said floor defining a chamber adapted to contain a molten aluminum pool in the lower portion thereof and a body of molten electrolyte above said molten aluminum pool and in contact therewith, at least one anode member disposed at least partially within said chamber and adapted to be in contact with the molten electrolyte, said arrangement of cathodic current-conducting elements consisting of at least one row across the shortest horizontal dimension of said cell, one extremity of each current-conducting element adapted to extend into said molten aluminum pool and the other extremity exposed to the atmosphere and connected to a metallic conductor, at least that portion of the surface of said current-conducting element in contact with said molten aluminum consisting essentially of refractory metallic compound.

2. A plurality of elongated electrolytic cells for the production of aluminum, said cells connected electrically in series and having an arrangement of cathodic current-conducting elements, each cell comprising refractory side and end walls, said side walls being relatively longer than said end walls, a floor of a refractory material, said walls and said floor defining a chamber adapted to contain a molten aluminum pool in the lower portion thereof and a body of molten electrolyte above said molten aluminum pool and in contact therewith, at least one anode member disposed at least partially within said chamber and adapted to be in contact with the molten electrolyte, said arrangement of cathodic current-conducting elements consisting of at least one row parallel to said end walls, one extremity of each current-conducting element being adapted to extend into said molten aluminum pool and the other extremity exposed to the atmosphere and connected to a metallic conductor, at least that portion of the surface of said current-conducting element in contact with said molten aluminum consisting essentially of refractory metallic compound.

3. A plurality of elongated electrolytic cells for the production of aluminum, said cells connected electrically in series and having an arrangement of cathodic current-conducting elements, each cell comprising refractory side and end walls, said side walls being relatively longer than said end walls, a floor of a refractory material, said walls and said floor defining a chamber adapted to contain a molten aluminum pool in the lower portion thereof and a body of molten electrolyte above said molten aluminum pool and in contact therewith, at least one anode member disposed at least partially within said chamber and adapted to be in contact with the molten electrolyte, said arrangement of cells being arranged in side by side relationship with a side wall of one cell parallel and adjacent to a side wall of a neighboring cell, said arrangement of cathodic, current-conducting elements consisting of cathodic current-conducting elements disposed vertically and transversely in at least one row across the longitudinal mid-section of each cell, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

4. A plurality of elongated prebake electrolytic cells for the production of aluminum, said cells connected electrically in series and having an arrangement of cathodic current-conducting elements, each cell comprising refractory side and end walls, said side walls being relatively longer than said end walls, a floor of a refractory material, said walls and said floor defining a chamber adapted

to contain a molten aluminum pool in the lower portion thereof and a body of molten electrolyte above said molten aluminum pool and in contact therewith, prebake anodes disposed at least partially within said chamber in rows parallel to the longitudinal axis of the cell and adapted to be in contact with the molten electrolyte, said cells being arranged in side by side relationship with a side wall of one cell parallel and adjacent to a side wall of a neighboring cell, said arrangement of cathodic, current-conducting elements consisting of cathodic current-conducting elements disposed vertically and transversely in at least one row across the longitudinal midsection of each cell, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

5. A plurality of elongated electrolytic cells for the production of aluminum, said cells connected electrically in series and having an arrangement of cathodic current-conducting elements, each cell comprising refractory side and end walls, said side walls being relatively longer than said end walls, a floor of a refractory material, said walls and said floor defining a chamber adapted to contain a molten aluminum pool in the lower portion thereof and a body of molten electrolyte above said molten aluminum pool and in contact therewith, at least one anode member disposed at least partially within said chamber and adapted to be in contact with the molten electrolyte, said cells being arranged in end-to-end relationship with an end wall of one cell parallel and adjacent to an end wall of a neighboring cell, said arrangement of cathodic current-conducting elements consisting of cathodic, current-conducting elements disposed transversely in at least one row across the downstream end of each cell, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

6. A plurality of elongated, self-baking anode electrolytic cells for the production of aluminum, said cells connected electrically in series and having an arrangement of cathodic current-conducting elements, each cell comprising refractory side and end walls, said side walls being relatively longer than said end walls, a floor of a refractory material, said walls and said floor defining a chamber adapted to contain a molten aluminum pool in the lower portion thereof and a body of molten electrolyte above said molten aluminum pool and in contact therewith, a self-baking anode disposed at least partially within said cell and adapted to be in contact with the molten electrolyte, said cells being arranged in end-to-end relationship with an end wall of one cell parallel and adjacent to an end wall of a neighboring cell, said arrangement of cathodic current-conducting elements consisting of cathodic, current-conducting elements disposed transversely in at least one row across the downstream end of each cell, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

7. A plurality of elongated electrolytic cells for the production of aluminum, said cells connected electrically in series and having an arrangement of cathodic current-conducting elements, each cell comprising refractory side and end walls, said side walls being relatively longer than said end walls, a floor of a refractory material, said walls

and said floor defining a chamber adapted to contain a molten aluminum pool in the lower portion thereof and a body of molten electrolyte above said molten aluminum pool and in contact therewith, at least one anode member disposed at least partially within said chamber and adapted to be in contact with the molten electrolyte, said cells being arranged in end-to-end relationship with an end wall of one cell parallel and adjacent to an end wall of a neighboring cell, said arrangement of cathodic current-conducting elements consisting of cathodic, current-conducting elements disposed vertically and transversely in at least one row across the downstream end of each cell, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

8. A plurality of elongated, self-baking anode electrolytic cells for the production of aluminum, said cells connected electrically in series and having an arrangement of cathodic current-conducting elements, each cell comprising refractory side and end walls, said side walls being relatively longer than said end walls, a floor of a refractory material, said walls and said floor defining a chamber adapted to contain a molten aluminum pool in the lower portion thereof and a body of molten electrolyte above said molten aluminum pool and in contact therewith, a self-baking anode disposed at least partially within said cell and adapted to be in contact with the molten electrolyte, said cells being arranged in end-to-end relationship with an end wall of one cell parallel and adjacent to an end wall of a neighboring cell, said arrangement of cathodic current-conducting elements consisting of cathodic, current-conducting elements disposed vertically and transversely in at least one row across the downstream end of each cell, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

9. A plurality of elongated electrolytic cells for the production of aluminum, said cells connected electrically in series and having an arrangement of cathodic current-conducting elements, each cell comprising refractory side and end walls, said side walls being relatively longer than said end walls, a floor of a refractory material, said walls and said floor defining a chamber adapted to contain a molten aluminum pool in the lower portion thereof and a body of molten electrolyte above said molten aluminum pool and in contact therewith, at least one anode member disposed at least partially within said chamber and adapted to be in contact with the molten aluminum, said cells being arranged in end-to-end relationship with an end wall of one cell parallel and adjacent to an end wall of a neighboring cell, said arrangement of cathodic, current-conducting elements consisting of at least one row of cathodic current-conducting elements disposed horizontally through and transversely across the downstream end wall of each cell, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

10. A plurality of elongated, self-baking anode electrolytic cells for the production of aluminum, said cells connected electrically in series and having an arrangement of cathodic current-conducting elements, each cell comprising refractory side and end walls, said side walls being relatively longer than said end walls, a floor of a refractory material, said walls and said floor defining a chamber adapted to contain a molten aluminum pool in the lower portion thereof and a body of molten electrolyte above said molten aluminum pool and in contact therewith, self-baking carbon anodes disposed at least partially within said cells and adapted to be in contact with the molten electrolyte, said cells being arranged in end-to-end relationship with an end wall of one cell parallel and adjacent to an end wall of a neighboring cell, said arrangement of cathodic, current-conducting elements consisting of at least one row of cathodic current-conducting elements disposed horizontally through and transversely across the downstream end wall of each cell, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

refractory material, said walls and said floor defining a chamber adapted to contain a molten aluminum pool in the lower portion thereof and a body of molten electrolyte above said molten aluminum pool and in contact therewith, self-baking carbon anodes disposed at least partially within said cells and adapted to be in contact with the molten electrolyte, said cells being arranged in end-to-end relationship with an end wall of one cell parallel and adjacent to an end wall of a neighboring cell, said arrangement of cathodic, current-conducting elements consisting of at least one row of cathodic current-conducting elements disposed horizontally through and transversely across the downstream end wall of each cell, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

11. A plurality of elongated electrolytic cells for the production of aluminum, said cells connected electrically in series and having an arrangement of cathodic current-conducting elements, each cell comprising refractory side and end walls, said side walls being relatively longer than said end walls, a bottom floor of a refractory material, said walls and said floor defining a chamber adapted to contain a molten aluminum pool in the lower portion thereof and a body of molten electrolyte above said molten aluminum pool and in contact therewith, at least one anode member disposed at least partially within said chamber and adapted to be in contact with the molten electrolyte, said arrangement of cathodic, current-conducting elements consisting of cathodic current-conducting elements disposed vertically and transversely in two rows across each cell, one row being substantially at each midpoint between the midsection and the end walls of the cell, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

12. A plurality of elongated, prebake electrolytic cells for the production of aluminum, said cells connected electrically in series and having an arrangement of cathodic current-conducting elements, each cell comprising refractory side and end walls, said side walls being relatively longer than said end walls, a bottom floor of a refractory material, said walls and said floor defining a chamber adapted to contain a molten aluminum pool in the lower portion thereof and a body of molten electrolyte above said molten aluminum pool and in contact therewith, prebake anodes disposed at least partially within said chamber in rows parallel to the longitudinal axis of the cell and adapted to be in contact with the molten electrolyte, said arrangement of cathodic, current-conducting elements consisting of cathodic current-conducting elements disposed vertically and transversely in two rows across each cell, one row being substantially at each midpoint between the midsection and the end walls of the cell, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

13. An elongated electrolytic cell for the production of aluminum comprising refractory side and end walls and having an arrangement of cathodic, current-conducting elements, said side walls being relatively longer than said end walls, a floor of a refractory material, said walls and said floor defining a chamber adapted to contain a

13

molten aluminum pool in the lower portion thereof and a body of molten electrolyte above said molten aluminum pool and in contact therewith, at least one anode member disposed at least partially within said chamber and adapted to be in contact with the molten electrolyte, said arrangement of cathodic, current-conducting elements consisting of cathodic current-conducting elements disposed in at least one row across the shortest horizontal dimension of said cell, one extremity of each current-conducting element adapted to extend into said molten aluminum pool and the other extremity exposed to the atmosphere and connected to a metallic conductor, at least that portion of the surface of said current-conducting element in contact with said molten aluminum consisting essentially of refractory metallic compound.

14. An elongated electrolytic cell for the production of aluminum comprising refractory side and end walls and having an arrangement of cathodic, current-conducting elements, said side walls being relatively longer than said end walls, a floor of a refractory material, said walls and said floor defining a chamber adapted to contain a molten aluminum pool in the lower portion thereof and a body of molten electrolyte contained in said chamber above said molten aluminum layer and in contact therewith, at least one anode member disposed at least partially within said chamber and adapted to be in contact with the molten electrolyte, said arrangement of cathodic, current-conducting elements consisting of cathodic current-conducting elements disposed in at least one row parallel to said end walls, one extremity of each current-conducting element being adapted to extend into said molten aluminum pool and the other extremity exposed to the atmosphere and connected to a metallic conductor, at least that portion of the surface of said current-conducting element in contact with said molten aluminum consisting essentially of refractory metallic compound.

15. An elongated prebake anode electrolytic cell for the production of aluminum comprising refractory side and end walls and having an arrangement of cathodic, current-conducting elements, said side walls being relatively longer than said end walls, a floor of a refractory material, said walls and said floor defining a chamber adapted to contain a molten aluminum pool in the lower portion thereof and a body of molten electrolyte above said molten aluminum pool and in contact therewith, prebake anodes disposed at least partially within said chamber in rows parallel to the longitudinal axis of the cell and adapted to be in contact with the molten electrolyte, said arrangement of cathodic, current-conducting elements consisting of cathodic current-conducting elements disposed vertically and transversely across the longitudinal midsection of said cell and being in the form of at least one row, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

16. An elongated electrolytic cell for the production of aluminum comprising refractory side and end walls and having an arrangement of cathodic, current-conducting elements, said side walls being relatively longer than said end walls, a floor of a refractory material, said walls and said floor defining a chamber adapted to contain a molten aluminum pool in the lower portion thereof and a body of molten electrolyte above said molten aluminum pool and in contact therewith, at least one anode disposed at least partially within said chamber, said arrangement of cathodic, current-conducting elements consisting of cathodic current-conducting elements disposed vertically and transversely across the downstream end of said cell and being in the form of at least one row, one extremity of each current-conducting element adapted to extend

14

5 into said molten aluminum pool, at least that portion of the surface of said current-conducting element in contact with said molten aluminum consisting essentially of at least one of the materials selected from the group consisting of the carbides and borides of titanium, zirconium, tantalum and niobium.

17. An elongated, self-baking anode electrolytic cell for the production of aluminum comprising refractory side and end walls and having an arrangement of current-conducting elements said side walls being relatively longer than said end walls, a floor of a refractory material, said walls and said floor defining a chamber adapted to contain a molten aluminum pool in the lower portion thereof and a body of molten electrolyte above said molten aluminum pool and in contact therewith, a self-baking anode disposed at least partially within said chamber and adapted to be in contact with the molten electrolyte, said arrangement of current-conducting elements consisting of current-conducting elements disposed vertically and transversely across the downstream end of said cell and being in the form of at least one row, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

18. An elongated electrolytic cell for the production of aluminum comprising refractory side and end walls and having an arrangement of cathodic, current-conducting elements, said side walls being relatively longer than said end walls, a floor of a refractory material, said walls and said floor defining a chamber adapted to contain a molten aluminum pool in the lower portion thereof and a body of molten electrolyte above said molten aluminum pool and in contact therewith, at least one anode disposed at least partially within said chamber and adapted to be in contact with the molten electrolyte, said arrangement of cathodic, current-conducting elements consisting of at least one row of cathodic current-conducting elements disposed horizontally through and transversely across the downstream end wall of said cell, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

19. An elongated, self-baking anode electrolytic cell for the production of aluminum comprising refractory side and end walls and having an arrangement of current-conducting elements, said side walls being relatively longer than said end walls, a floor of a refractory material, said walls and said floor defining a chamber adapted to contain a molten aluminum pool in the lower portion thereof and a molten electrolyte above said molten aluminum layer and in contact therewith, a self-baking anode disposed at least partially within said cell and adapted to be in contact with the molten electrolyte, said arrangement of current-conducting elements consisting of at least one row of current-conducting elements disposed horizontally through and transversely across the downstream end wall of said cell, one extremity of each current-conducting element adapted to extend into said molten aluminum pool, at least that portion of the surface of said current-conducting element in contact with said molten aluminum consisting essentially of at least one of the materials selected from the group consisting of the carbides and borides of titanium, zirconium, tantalum and niobium.

20. An elongated, prebake anode electrolytic cell for the production of aluminum comprising refractory side and end walls and having an arrangement of cathodic,

current-conducting elements, said side walls being relatively longer than said end walls, a bottom floor of a refractory material, said walls and said floor defining a chamber adapted to contain a molten aluminum pool in the lower portion thereof and a body of molten electrolyte above said molten aluminum layer and in contact therewith, prebake anodes disposed at least partially within said chamber in rows parallel to the longitudinal axis of the cell, said arrangement of cathodic, current-conducting elements consisting of cathodic current-conducting elements disposed vertically and transversely in two rows across the cell, one row being substantially at each midpoint between the midsection and the end walls of the cell, one extremity of each current-conducting element adapted to extend into said molten aluminum pool, at least that portion of the surface of said current-conduct-

ing element in contact with said molten aluminum consisting essentially of at least one of the materials selected from the group consisting of the carbides and borides of titanium, zirconium, tantalum and niobium.
